TUNING KEY

George F. Gregg, Yakima, Wash.

Application July 2, 1946, Serial No. 681,087

1 Claim. (Cl. 84—306)

1

The present invention relates to improvements in tuning keys for musical stringed instruments.

One of the objects thereof is to provide a simple, efficient and inexpensive tuning key so shaped, arranged and functioning that it provides at all times a sturdy, dependable, and efficient device of this character when applied to the neck of the instrument.

Another object thereof is to provide a means of rapidly installing the strings of stringed musical instruments and to rapidly and easily bring such strings to the tension required to provide the desired pitch.

Another important object thereof is to render it impossible, by means of the present tuning key, to wind on the string the wrong way and by enclosing the gears it is assured that the accumulation of dust and other foreign matter in the working parts is avoided.

A still further object thereof is to provide a tuning key for particular use upon the solid heads of musical instruments as put out by manufacturers today.

A further object thereof is to provide a novel tuning key which is entirely enclosed within the solid head of the instrument so as to protect the working parts from foreign matter and render it easy to disassemble the parts when desired for repair or replacements.

With the above and other objects in view my invention consists in the combination, arrangement and details of construction disclosed in the drawings and specification, and then more particularly pointed out in the appended claim.

In the drawings, wherein similar reference characters designate similar parts throughout the respective views,

Figure 1 is an elevation, partly in section of my tuning key invention,

Figure 2 is a sectional elevation of my invention, taken at right angles to Figure 1, and

Figure 3 is a section taken on line 3—3 of Figure 2.

Referring to the drawings, which are merely illustrative of my invention the various parts thereof are disclosed. A gear case is provided in the shape of a box having the side walls 13, 14, end walls 11, 12 and the closed top plate 21 operatively carried by the case or box. The hollow interior of the case is designated 15.

The box is generally designated 10. There is a shaft 16 carrying a hand thumb head 17. This shaft 16 extends into the interior 15 of the case or box 10. It will be seen from Figure 1 that the shaft, between its ends, as at 18 projects

2

into side wall 13 of the case, while its innermost end 19 projects through side wall 14 thereof. In this manner this shaft 16 is journaled in the case. Shaft 16 is formed with a worm, the convolutions of which are designated 20. The worm extends across the effective width of the case or box, in such a way that one end of the worm 21 abuts side wall 13 of the case while the other end 22 abuts the side wall 14. In this way the worm snugly is enclosed rotatably by the case.

The worm meshes with a worm wheel or gear 23 carried at the lower end of a vertical shaft 25. This worm gear is held in position, made fast upon the shaft end by aid of a securing screw 24 tapped into the end of the shaft 25. The shaft 25 rotatably projects through the block 22 which rests upon the top plate 21 of the box or case. The shaft 25 has a longitudinal bore in which extends the lower portion 26 of a post or rod or elongated pin made of a length longer than the shaft 25. The post 26 is held rigidly in the shaft 25 so as to be firmly anchored therein by means of a set screw 28 tapped through the block 22 into shaft 25 in a manner to bind the post 26 in the shaft 25.

There is another shaft 29, of the same diameter as shaft 25. It is designated 29 and it has an internal elongated bore 30 into which the other portion or end, 27, of the rod or post slidably extends telescopically. The confronting ends of both shafts 25 and 29 are formed with jagged clutch surfaces in the form of a circular series of serrations 31 on the lower end of shaft 29 and a circular series of serrations on the outer end of shaft 25.

The shaft 29 is formed with a diametrical hole 38. It is formed in back of this hole with an annular groove or seat 35 into which snaps a resilient split ring 34 which acts as a stop for a collar. This collar 36 embraces the shaft 29 slidably and it is engaged by the split ring 34 as a stop member therefor. At the outer end of the shaft 29 is a flanged screw. The screw 49 thereof is tapped coaxially into the outer end of the shaft 29, while the integral flange 39 on this screw engages against the outermost end of the shaft 29 abuttingly when the screw is driven home into the shaft. The musical instrument string is inserted in hole 38 as is understood by those skilled in the art.

In operation, when the shaft 29 is gently pushed in and turned, the slack is immediately taken out of the string. This is done by taking hold of the thumb piece 17, turning shaft 16 and causing the lower vertical shaft 25 to turn; depressing of the

upper shaft 29 engages its clutch teeth or serrations 21 with the clutch teeth 32 on the lower shaft, so now both shafts are engaged for unitary rotation. Rotation of shaft 25 thus effects rotation of the shaft 29. In this way the string is put under tension by a slight winding thereof on shaft 29. The worm convolutions 28 lock the shafts 25 and 29 in adjusted relation with respect to the tensioned string.

The tuning key is attached to the neck of the musical stringed instrument where now tuning keys are located. Because of the clutch serrations formed separately upon both shaft sections 25 and 29, the upper vertical shaft section 29 is free to turn in a clockwise direction. Pressure applied to turn this shaft in a clockwise direction causes the serrations on the lower portion of upper shaft 29 to engage the serrations on the lower shaft and so lock the shafts securely.

The collar 36, when engaging the neck of the instrument properly keeps shaft 29 firmly in place as it holds against movement the shaft 29 by engagement of this shaft with the stop ring 34. The shaft 29 can slide relatively to and in this collar when the latter is in fixed position about one eighth of an inch and then snap ring 34 engages the collar.

It will thus be seen that the present tuning key fits into holes placed in the head of the stringed instrument. It provides for ready and rapid tuning of string installations, the speed being limited only by the speed of the worm gearing. This worm gearing allows for a fine adjustment of the sectional shaft. Not only is a fine adjustment made possible ultimately by the worm gearing thereof, but a rapid coarse initial adjustment is made possible by allowing the shaft 29 to turn freely of the worm gear. In this way strings may always be installed quickly and accurately and have long life. As the gearing is encased or enclosed at all times it is significant to note that the device is constantly kept free from dust and dirt and in no wise does the device change the outside appearance of the instrument.

I do not intend to confine myself to the exact details of construction herein disclosed save as pointed out in the appended claim.

What I desire to claim is:

- 5 In a tuning key for stringed musical instruments, including a worm wheel, means for manually rotating said wheel, a worm gear in mesh with said wheel, the improvement comprising a shaft fixed to said gear and extending axially thereof, said shaft including a free end formed to provide ratchet clutch teeth, said shaft being formed with an axial bore, a cylindrical rod fixed in said bore and extending axially outwardly of said free end, a sleeve slidable and rotatable on said rod, said sleeve including an inner end formed to provide ratchet clutch teeth complementary to said first teeth and engageable therewith, said sleeve including an outer end formed to provide a winding knob, said sleeve being formed 15 with a transverse aperture for connecting an instrument string thereto, said sleeve being slidable on said rod in one direction to disengage said teeth and permit a coarse tightening of said string upon rotation of said sleeve by said knob, and a 20 threaded connection between said knob and sleeve to compel unidirectional manual rotation of said sleeve to coarsely tighten said string.

GEORGE F. GREGG.
